US0D1049020S

(12) **United States Design Patent** (10) Patent No.: **US D1,049,020 S**
(45) Date of Patent: ** Oct. 29, 2024

(54) **BATTERY**

(71) Applicant: **Apower Electronics Co., Ltd (AEC)**,
Guangdong (CN)

(72) Inventors: **Jack Chen**, Guangdong (CN); **Guoyan Zuo**, Guangdong (CN); **Linhai Huang**, Guangdong (CN); **David Guo**, Guangdong (CN)

(73) Assignee: **Apower Electronics Co., Ltd (AEC)**,
Guangdong (CN)

(**) Term: **15 Years**

(21) Appl. No.: **29/726,292**

(22) Filed: **Mar. 2, 2020**

(30) **Foreign Application Priority Data**

Jan. 15, 2020 (CN) 202030026637.4

(51) LOC (14) Cl. **13-02**

(52) U.S. Cl.

USPC **D13/103**
